UNITED STATES PATENT OFFICE.

GEORGE MELLOR, OF PHILADELPHIA, PENNSYLVANIA.

SPARK-PLUG CLEANER.

1,378,182.

Specification of Letters Patent. Patented May 17, 1921.

Application filed March 20, 1918. Serial No. 223,608.

To all whom it may concern:

Be it known that I, GEORGE MELLOR, a citizen of United States, residing at 1947 N. 19th St., Philadelphia, in the county of 5 Philadelphia and State of Pennsylvania, have invented new and useful Improvements in Spark-Plug Cleaners, of which the following is a specification.

The invention relates to spark plugs, and 10 more particularly to cleaning devices therefor, and has for an object to provide a simple device that can be cheaply manufactured, and which is adapted to effectively clean spark plugs, and more particularly 15 the contact points thereof, for the purpose of removing any carbon or other deposits which ordinarily tend to incrust or deposit themselves upon the contact points, and thus destroy the efficiency of the spark plug.

20 Among other features, the invention comprehends a simple device which consists of few parts, and in fact the body of which is formed of a single piece of material that can be crushed or bent to form a holder for suitable 25 brushes, and also carry scraping elements, so that the spark plug can be subjected to several operations by use of the device to effectively clean the contact points of the plug.

30 In the further disclosure of the invention, reference is to be had to the accompanying drawing, constituting a part of this specification, in which similar characters of reference denote corresponding parts in all the 35 views, and in which—

Figure 1 is a plan view of the spark plug cleaner.

Fig. 2 is a fragmentary horizontal sectional view taken through the spark plug cleaner, showing details of construction.

40 Fig. 3 is a transverse sectional view through the scraping and cleaning part of the cleaner, and

Fig. 4 is a perspective view of the blank 45 from which the body of the spark plug cleaner can be made.

Referring more particularly to the views, and especially to Figs. 1, 2 and 4, I employ a cylinder 10 of metal that can be readily 50 bent or crushed without breaking or cracking, said cylinder to constitute the body 11 of the cleaner. The end 12 of the body has a wire brush 13 secured therein, and the end 12 is then crushed down upon the inner 55 ends of the wire strands of the brush, thus holding the strands forming the brush

firmly together, and in rigid engagement with the interior of the body. The other end 14 of the body is similarly treated by securing thereto a bristle brush 15, the inner 60 portion of the brush being secured in the body and the body then crushed down, as shown at 14, rigidly securing the bristle brush in position, it being particularly noted, however, that the bristle brush lies at right 65 angles to the wire brush 13. The medial portion of the body now receives a quantity of fine piano or other wire 16, which is wound around the cylinder 10, and that portion of the cylinder with the wire 16 around 70 it is then crushed flat, and thus crushing the wire flat to provide scraping surfaces 17 and, in fact, a scraping portion or element 18, which scraping portion is formed by the crushed wire, and is somewhat in the 75 nature of a filing surface, being rough, due to the texture of the wire and the crushing of the wire when the body is crushed. The ends of the wire can be secured to the body by suitable pieces of solder, as shown at 19, 80 or in any other convenient manner, and it will be clearly seen by reference to Fig. 2 that by having the cylinder 10 crushed to form the different parts mentioned heretofore, the fibers or bristles of the brushes 13 85 and 15 can not be pushed inwardly any farther, due to the fact that in crushing down the medial portion of the cylinder 10, converging portions 20 will be formed thereby, and these will limit any inward movement of the fibers or bristles of the brushes, the flattening of the ends of the body preventing the removal of the fibers or bristles 90 of the brushes.

It will clearly be seen that in use, when 95 it is desired to clean a spark plug, the spark plug is removed from the particular piece of machinery with which it may have been connected or associated, and by means of the wire brush the contact points of the 100 spark plug can be cleaned of any deposits of carbon or the like, and if necessary the contact points can be further cleaned or scraped by subjecting them to the roughened scraping surfaces 17, which surfaces 105 may first be moistened with gasoline so that the scraping action on the contact points will effectively remove the deposits, and result in a clean, smooth surface capable of electric conductivity. Finally, the bristle 110 brush 15 can be employed to dry off any gasoline or particles of the material that

has been scraped from the contact points, and thus it will be apparent that the device described provides a compact and effective tool for the purpose mentioned.

5 I claim:

A spark plug cleaner comprising a longitudinal extended body with end cleaners thereon and having an intermediate flattened portion and scraping surfaces on said body portion consisting of a quantity of fine wire

tightly wound around said flattened portion with the convolutions of the wire in contact with each other and with the ends of the wire secured to the body whereby said scraping surfaces will be rigid and immovable relative to said body and held against any longitudinal or transverse movement on the flattened portion thereof. 15

In testimony whereof I affix my signature.
GEORGE MELLOR.
